MULTICELLULAR CARRIERS

Marshall I. Williamson, New Haven, Conn., assignor to Federal Paper Board Company, Inc., Bogota, N.J., a corporation of New York

Application July 19, 1957, Serial No. 673,067

6 Claims. (Cl. 229—28)

This invention relates to improvements in multicellular carriers of the twin-row type for the packaging, as a sales unit, of a plurality of bottles or other receptacles arranged in two parallel rows.

The invention more particularly relates to the type of carrier in which individual cells are formed in the top structure by deflection of portions of the top panel into a vertical position so as to form a receptacle-engaging cell wall or liner, other portions of the top structure remaining in a generally horizontal position to provide spacers for separating the receptacles of each row from one another.

Carriers of the aforementioned type are usually equipped with a central handle arranged between the two rows of receptacles. If this handle is extended above the tops of the receptacles, it interferes with the stacking of loaded carriers into display pyramids, a common practice in grocery stores. The handle also requires a substantial amount of board.

Short handles terminating below the tops of the receptacles are inconvenient for the customer because of the narrow space between the rows of receptacles and is particularly uncomfortable to use if the receptacles are bottles sealed by a crown type cap. These caps have a coarsely knurled or serrated periphery comprising sharp points which uncomfortably dig into the hand of the person lifting the carrier.

The invention provides, among other features, an improvement, as a result of which the space between the bottle caps of the two rows of bottles is automatically increased when the carrier is lifted up. This is accomplished by a tapered design, in end view, of the two halves of the bottle carrier which are widest near the base of the cell apertures and narrowest at the bottom. The two halves are articulated to each other at or near the widest portion so that, when the carrier rests on a flat surface, the two halves are spaced at the bottom. When lifted up the two halves tilt relatively to the handle, closing the space which previously existed at the bottom, and increasing the space between the two rows of the bottle tops, whereby an adequate and comfortable space for the hand of the person carrying the device is gained.

Other improvements involve an automatic shift in the load distribution of the carrier. In the position in which the carrier rests on the flat surface the load may be considered to be evenly distributed over the bottom panel. When the carrier is lifted up, a greater portion of the load is carried by the bottom panel adjacent the handle wall structure, thereby relieving the outer wall structure of a portion of the load. This is an important advantage in a construction in which the cellular top structure is joined to the inner walls by a glue lap. The load sustained by the outer walls is transferred to the handle via the cellular top structure and the glue lap and there is a tendency of the glue lap to pull away from the inner walls. The tendency of the glue lap pulling away is sub-

2

stantially reduced if the center of the load is shifted towards the center.

These and other objects, features and advantages of the invention will appear more fully from the detailed description showing, for the purpose of illustration, a preferred embodiment of the invention. The invention also resides in certain new and original features of construction and a combination of elements hereinafter set forth and claimed.

10 Although the characteristic features of this invention which are believed to be novel will be particularly pointed out in the claims appended hereto, the invention itself, its objects and advantages, and the manner in which it may be carried out, may be better understood by referring to the following description, taken in connection with the accompanying drawings forming a part of it, in which:

Figure 1 is a plan view of a cut and scored flat blank from which a twin-row carrier embodying the present invention may be formed, the inside surface facing the observer;

Figure 2 is a plan view of the blank of Figure 1 after certain folding and gluing operations converting the blank into a flat collapsed tubular structure;

25 Figure 3 is a perspective view of the tubular structure of Figure 2 after expansion, preparatory to the formation of the cells;

Figure 4 is a perspective view of the structure of Figure 3 after formation of the cells;

30 Figure 5 is a perspective view of the multicellular structure of Figure 4 in combination with a handle, ready for loading with bottles or other receptacles or articles of merchandise;

Figure 6 is an end elevation of the multicellular structure of Figure 4 in a position in which the structure rests on a flat surface;

Figure 7 is an end elevation of the structure of Figure 6 after lifting up from the supporting surface;

40 Figure 8 is a perspective view illustrating the bottle separation produced by the lifting up of the multicellular structure; and

Figures 9 and 10 are end elevations of multicellular structures of the type shown in Figure 4, having center walls of different height.

45 In the following description and in the claims various details will be identified by specific names for convenience. The names however are intended to be generic in their application. Corresponding reference characters refer to corresponding parts in the several figures of the drawings.

50 The drawings accompanying, and forming part of, this specification disclose certain specific details of the invention for the purpose of explanation of its broader aspects, but it is understood that the details may be modified in various respects without departure from the principles of the invention and that the invention may be applied to other structures than the ones shown.

The blank A of Figure 1 consists of suitable foldable sheet material such as paperboard. The blank is rectangular in outline and may be cut and scored, in multiple, on automatic cutting and creasing machines. The several constituent parts of the blank are set apart by fold lines and cuts.

60 The blank A comprises a glue lap 11, an upper inner wall panel 12, a top wall panel 13, an outer wall panel 14, a bottom panel 15, an inner wall panel 16, a further inner wall panel 17, a further bottom panel 18, a further outer wall panel 19, a further top panel 20, a further upper inner wall panel 21, and a further glue lap 22. The various panels are articulated to one another along substantially parallel fold lines of which 23 may be termed a glue lap fold line, 24 and 25 top fold lines, 26 and 27 bottom fold lines, 28 at center partition ridge fold line,

29 and 30 bottom fold lines, 31 and 32 top fold lines and 33 a further glue lap fold line.

The width of the top panels 13 and 20, measured between their respective top fold lines 24, 25, and 31, 32, is equal to the width of the bottom panels 15 and 18, measured between their respective bottom fold lines 26, 27 and 29, 30. These dimensions, as will later be seen, permit the blank to be collapsed flat in glued condition.

The inner wall panels 16 and 17 are subdivided into upper portions 34, 35 and lower portions 36, 37 by intermediate folding scores 38 and 39, the significance of which will appear later.

The top panels 13 and 20 are traversed by cuts and fold lines permitting the formation of individual merchandise receiving cells therein. These cuts and fold lines may be identical for all the cells, and it will be sufficient to describe the configurations within the top panel 13, it being understood that top panel 20 is of the same layout.

Cell cuts 40, 41 and 42 extend across the top panel and continue beyond the top fold lines 24 and 25 into the body of the outer wall panel 14 and of the upper inner wall panel 12, respectively. The cell cuts terminate at relatively short transverse cuts 43, 44, 45, 46, 47, 48. The transverse cuts 43, 45 and 47 are substantially in line 25 with the glue lap fold line 23 and terminate at apex points 49, 50, 51, 52, 53 and 54. Similar apex points 55, 56, 57, 58, 59 and 60 mark the ends of the opposite transverse cuts 44, 46 and 48. An additional fold line 61 may be provided in line with the apex points 55, 56, 57, 58, 59 and 60, but this fold line 61 is optional.

The area of board on either side of the cell cuts 40, 41 and 42 is circumscribed by fold lines of a generally polygonal, somewhat elongated outline. These fold lines comprise diagonal lines 62, 63, 64, 65, 66 and 67 extending from the respective apex points 49, 50, 51, 52, 53 and 54. Similar diagonal fold lines 68, 69, 70, 71, 72 and 73 extend from the apex points 55, 56, 57, 58, 59 and 60. The diagonal fold lines extend at an angle of substantially 45 degrees to the top fold lines 24 and 25. Further fold lines 74, 75, 76, 77, 78 and 79 extend from the ends of the diagonal fold lines and lead to peak points 80, 81, 82 and 83. Corresponding fold lines within the other half of the top panel are numbered 84, 85, 86, 87, 88 and 89.

It is readily seen that the diagonal fold lines form the sides of trapezoidal panel portions 90, 91, 92 and 93, above which substantially triangular panel portions 94, 95, 96 and 97 arise. The peaks of the triangle meet at the peak points 81 and 82 in the preferred form of cell construction illustrated in the drawings. A central fold line 98 extends down the center of the top panel 13. Auxiliary fold lines 99, 100, 101, 102, 103 and 104 may be provided to facilitate the formation of the cell structure later to be described.

The construction of a multicellular box from the blank A of Figure 1 may proceed by treating both ends of the blank substantially alike, as follows:

Adhesive α is first applied to the underside of the glue laps 11 and 12 and the blank is then folded along the top fold lines 24 and 32 to bring the glue laps 11 and 22 into a position over the top wall panels 13 and 20, respectively. Next, the ends of the blank are folded about the fold lines 26 and 30 to bring the glue laps 11 and 22 into adhesive engagement with the lower portions 36 and 37 of the inner walls.

The folding operations produce a flat collapsed tubular structure A' shown in Figure 2. The collapsed structure A' may be stored and shipped in flat condition, requiring a minimum of space, and may be set up into hollow multicellular box form by a few relatively simple folding operations which will now be described.

The collapsed structure A' is readily expanded and folded along the center partition ridge fold line 28. The expanded structure is shown in Figure 3.

In the expanded structure the inner wall panels 16 and

17 lie back to back for their entire extent including the lower portions 36 and 37. The top panels 13 and 20 are parallel to the bottom panels 15 and 18. The side wall panels 14 and 19 are parallel to the inner wall panels 16 and 17. As previously stated, the width of the top panel is equal to the width of the bottom panel. This construction permits the structure of Figure 3 to be prefabricated in flat collapsed condition and, also, to be recollapsed, if that should be desired.

In the structure shown in Figure 3 individual cells are formed by downfolding of the portions of the top panels which lie immediately adjacent the respective cell cuts 40, 41 and 42. The board is readily folded at the diagonal fold lines 62, 63, 64, 65, 66 and 67 and at the corresponding fold lines on the other side 68, 69, 70, 71, 72 and 73 and thereafter assumes a substantially vertical position with respect to the bottom panel, as shown in Figure 4. The auxiliary fold lines 99, 101 and 103, visible in Figure 4, and the auxiliary fold lines 100, 102 and 104, which are not visible, aid in the folding of the board into vertical position.

The cell forming operation causes the points 80, 81, 82 and 83 to rise as peaks above the remainder of the top panel. The triangular portions 94, 95, 96 and 97 assume a slanted position by reason of which the top fold lines 24 and 25 are drawn together to assume a distance T (Figure 6) less than the original width of the top panel which was equal to the width B of the bottom panel.

As a further consequence of the formation of the cells, the upper portion of the walls assume an inwardly slanted position. Thus the upper inner wall panels 12 and 21, which previously lay flat against the inner wall panels 16 and 17, are separated therefrom as clearly seen in Figures 4 and 6. Similarly the corresponding upper portion of the outer walls 14 and 19 is drawn inwardly to form a slanted position with regard to the lower portion of the outer wall panels 14 and 19.

The cell structure which is mainly contained in the top panels, but also extends into the upper portions of the side walls, resembles a mansard roof in end view, as is clearly apparent from Figure 6. This shape causes the cells to open to a maximum dimension C measured at the widest point, substantially at the level of the intermediate folding scores 23, 33, opposite which the optional fold lines 61 lie. In the event the fold lines 61 are omitted, the outer walls are arched or bowed and the dimension C is measured between the respective transverse cuts 44, 46, 48 and the glue lap fold line 23, coinciding with the transverse cuts 43, 45, 47.

Referring to Figure 6, the wall panels 14 and 36 are upwardly and outwardly slanted with regard to the bottom panel 15. Likewise, the lower portions of the wall panels 37 and 19 are outwardly and upwardly slanted with respect to the bottom panel 18.

Since both cell structures are hingedly connected at the intermediate folding scores 38, 39, the lower portions 36, 37 of the inner wall panels separate to form a space S between them.

Figure 6 shows the cellular structure to be loaded with 60 bottles 105, 106 whose axes 107 and 108 are vertical as long as the structure rests on a flat substantially horizontal supporting surface 109. The bottles are snugly held within the vertical wall portions of the cells and are readily inserted since the dimension C is larger than the diameter of the bottles. Similarly, the distance between the peaks 80, 81, 82 and 83 is larger than the bottle diameter due to the fact that, as a geometrical necessity, these points are spaced farther than opposite surfaces of the vertical cell walls.

In the position shown in Figure 6 the weight of the bottles is equally distributed over the surface of the bottom panels 15 and 18 as indicated by the diagram 110 in which the load is plotted vertically and in which the horizontal axis represents the width of the bottom

panel, or the bottle diameter. The resultant or total load is represented by the centrally disposed arrow L.

If the structure is lifted up by a force F, as indicated in Figure 7, the two halves of the carrier tilt relatively to each other about the intermediate folding scores 38, 39 until the lower portion 36, 37 of the inner walls 16 and 17 rest against each other. In this condition the bottom panels 15 and 18 are tilted.

Since each cellular structure essentially represents a parallelogram in end elevational view, its outer walls 14 and 19 tend to sag slightly causing the bottom panels 15 and 18 to separate somewhat from the bottoms of the bottles near the outer walls 14 and 19, as is visible at 111 and 112 in Figure 7. As a result, a shift occurs in the load distribution which is represented by the diagram 113. The diagram shows that the load is carried predominantly near the inner walls 16 and 17. The resultant load L, which was centrally disposed in the diagram 110 of Figure 6, was shifted an appreciable distance towards the central partition 16, 17. In the position shown in Figure 7 the outer walls 14 and 19 carry relatively little of the total load. As a result, less load is transmitted through the cellular top structure to the glue lap and the danger of separation of the glue laps 11 and 22 from the inner wall structure is greatly reduced.

The axes of the bottles are tilted outwardly in Figure 7, thus providing increased clearance between the tops of the bottles. This is also seen in Figure 8 where the crown caps 114 and 115 of the center bottles are spaced a safe and comfortable distance from the hand 116 of the person lifting the carrier. The carrier may be lifted either by an attached handle, as shown in Figure 8, or by a suitable hand aperture in the inner wall structure 16, 17.

When the loaded multicellular structure of Figure 7 is placed on a flat surface, the multicellular units again separate and assume the position shown in Figure 6.

Figure 5 illustrates a preferred form of attachable and detachable handle for the multicellular structure A" of Figure 4. The handle 117 forms the subject matter of a copending application Serial No. 672,991, filed July 19, 1957, and consists, essentially, of a single blank of paperboard folded back on itself along a top fold line 118.

The handle is provided with flaps 119 articulated along flap fold lines 120. The flaps are folded back upon the handle, while the handle is in flat condition, whereafter the handle is creased along vertical fold lines 121. In this condition the flaps 119 cannot unfold, since they are tightly drawn against the body of the handle, the flap fold line 120 being bent at each vertical fold line 121.

The handle 117 is inserted into the central cells and hooks under the walls of the central cells.

In order to facilitate the engagement of the handle with the walls of the central cells, the blank may be provided with a cutout 123 providing a recessed lower edge 122 (Figure 4) within the central cells. The cutout provides a substantially horizontal engaging edge 122 for the handle in the position in which the halves of the carrier are tilted as shown in Figure 7. In this position the bottom edges 124 of the cell webs are slanted, but the cutout 123 provides a horizontal engaging edge portion for the handle.

Figures 9 and 10 illustrate minor modifications of the blank of Figure 1. In Figure 9 the inner walls 16 and 17 extend only to the hinge axis between the two cellular structures. In this form the center partition ridge fold line 28 may be considered to coincide with the hinge line provided by the intermediate folding scores 38, 39. In the form shown in Figure 10 the inner walls 16 and 17 are taller than in Figure 9, but lower than in Figure 4. In this modification the center partition ridge fold line 28 is approximately at the same level as the top fold lines 24 and 32 and the two cellular units are articulated to each other along intermediate folding scores 38, 39.

What is claimed is:

1. A multicellular flat collapsible folding box of the twin-row style formed from a single blank of board and comprising two tubular structures arranged side by side, each structure comprising a bottom panel; an outer side wall and an inner side wall articulated to the bottom panel along bottom fold lines, the inner side wall comprising an upper wall panel and a lower wall panel; a top panel articulated to the side walls along top fold lines, the top panel being arched to rise above said top fold lines and having cells in it, the mouth of the cells extending beyond said top fold lines into the body of said side walls, said cells including depending cell walls integral with said top panel and depending therefrom at the cell mouth towards the bottom panel, each of the inner side walls of the two structures including an intermediate folding score intermediate of, and substantially parallel to, said top and bottom fold lines to which intermediate folding score said cell apertures extend, each of said inner side walls further comprising a glue lap articulated to said upper wall panel and adhered to the lower wall panel adjacent said intermediate folding score, the width of the bottom panel measured between the bottom fold lines being less than the width of the structure measured at the level of the intermediate folding score, said two structures being pivotally movable relatively to each other at said intermediate folding score for freedom of the structures to tilt towards each other when the box is centrally lifted up, in which event the bottom panels assume slanted positions and the cell axes tilt outwardly, and for freedom to tilt in the opposite direction when the bottom panels are placed on a flat support, in which event the bottom positions of the two units automatically separate.

2. A multicellular flat collapsible folding box of the twin-row style formed from a single blank of board and comprising two tubular structures arranged side by side, each structure comprising a bottom panel; an outer side wall and an inner side wall articulated to the bottom panel along bottom fold lines, the inner side wall comprising an upper wall panel and a lower wall panel; a top panel articulated to the side walls along top fold lines, the width of the top panel in flat condition being equal to the width of the bottom panel, width being measured between the respective bordering fold lines, the top panel being arched to rise above said top fold lines and having cells in it, the mouth of the cells extending beyond said top fold lines into the body of said side walls, said cells including depending cell walls integral with said top panel and depending therefrom at the cell mouth towards the bottom panel, each of the inner side walls of the two structures including an intermediate folding score intermediate of, and substantially parallel to, said top and bottom fold lines to which intermediate folding score said cell apertures extend, each of said inner side walls further comprising a glue lap articulated to said upper wall panel and adhered to the lower wall panel adjacent said intermediate folding score, the width of the bottom panel being less than the width of the structure measured at the level of the intermediate folding score, and greater than the distance between the top fold lines when the top panel is in arched position, said two structures being pivotally movable relatively to each other at said intermediate folding score for freedom of the structures to tilt towards each other when the box is centrally lifted up, in which event the bottom panels assume slanted positions and the cell axes tilt outwardly, and for freedom to tilt in the opposite direction when the bottom panels are placed on a flat support, in which event the bottom portions of the two units automatically separate.

3. A multicellular flat collapsible folding box of the twin-row style formed from a single blank of board and comprising two tubular structures arranged side by side, each structure comprising a bottom panel; an outer side wall, and an inner side wall articulated to the bottom panel along bottom fold lines; a top panel articulated to the outer side wall along a top fold line, an upper inner

wall panel articulated to said top panel along a further top fold line; and a glue lap articulated to said upper inner wall panel along a further glue lap fold line and adhered to the inner side wall, the top panel being arched to rise above said top fold lines and having cells in it, the mouth of the cells extending beyond said top fold lines into the body of said side walls, said cells including depending cell walls integral with said top panel and depending therefrom at the cell mouth towards the bottom panel, the inner side walls of the two structures being taller than the outer side walls and being articulated to each other along a center partition ridge fold line, each of the inner side walls including an intermediate folding score intermediate of, and substantially parallel to, said top and bottom fold lines, to which intermediate folding score said cell apertures extend, said glue laps being adhered to said inner walls adjacent said intermediate folding score, said further top fold line being in substantial coincidence with said intermediate folding score, the width of the bottom panel measured between the bottom fold lines being less than the width of the structure measured at the level of the intermediate folding score, said two structures being pivotally movable relatively to each other at said intermediate folding score for freedom of the structures to tilt towards each other when the box is centrally lifted up, in which event the bottom panels assume slanted positions and the cell axes tilt outwardly, and for freedom to tilt in the opposite direction when the bottom panels are placed on a flat support, in which event the bottom portions of the two units automatically separate.

4. A multicellular folding box as claimed in claim 3 in which the inner side walls are provided with a finger grip aperture below said center partition ridge fold line and above said intermediate folding score.

5. A multicellular flat collapsible folding box of the twin-row style formed from a single blank of board and comprising two tubular structures arranged side by side, each structure comprising a bottom panel, an outer side wall panel articulated to said bottom panel along an outer bottom fold line, a top panel articulated to said outer side wall panel along a top fold line, an upper inner side wall panel articulated to the top panel along a further top fold line, a glue lap articulated to said upper inner side wall panel along a glue lap fold line, and a lower inner side wall panel articulated to said bottom panel along an inner bottom fold line, the lower inner wall panels of the two structures being articulated to each other along a center ridge fold line, the top panel of each structure being arched to rise above said top fold lines and having cells in it, the mouth of the cells extending beyond said top fold lines into the body of the outer and of the upper inner side walls, said cells including depending cell walls integral with said top panel and depending therefrom at the cell mouth towards the bottom panel, said glue laps being adhered to the inner side walls adjacent said center ridge fold line to which intermediate folding score said cell apertures extend, the glue lap fold line being in substantial coincidence with said center ridge fold line, the width of the bottom panel measured

between the bottom fold lines being less than the width of the structure measured at the level of the intermediate folding score, said two structures being pivotally movable relatively to each other at said intermediate folding score for freedom of the structures to tilt towards each other when the box is centrally lifted up, in which event the bottom panels assume slanted positions and the cell axes tilt outwardly, and for freedom to tilt in the opposite direction when the bottom panels are placed on a flat support, in which event the bottom portions of the two units automatically separate.

6. A multicellular flat collapsible folding box of the twin-row style formed from a single blank of board and comprising two tubular structures arranged side by side, each structure comprising a bottom panel; an outer wall panel articulated to said bottom panel along a bottom fold line, said outer wall panel having a lower portion and an upper portion, said two portions being articulated to each other along an intermediate outer folding score parallel to said bottom fold line, the lower portion being outwardly slanted and the upper portion being inwardly slanted; a top panel articulated to said upper portion along a top fold line; an upper inner wall panel articulated to said top panel along a further top fold line; a glue lap articulated to said upper inner wall panel along a glue lap fold line; a lower inner wall panel articulated to said bottom panel along a further bottom fold line, said lower inner wall panel also being outwardly slanted and having said glue lap adhered to it in a position in which the glue lap fold line has substantially the same distance from the bottom panel as the said intermediate folding score, the lower inner wall panels being articulated to each other along a center ridge fold line, said top panel being arched to rise above said top fold lines and having cells in it, the mouth of the cells extending beyond said top fold lines to said intermediate folding score and said glue lap fold line respectively, said cells including depending cell walls integral with said top panel and depending therefrom at the cell mouth towards said bottom panel, the width of the bottom panel measured between the bottom fold lines being less than the width of the structure measured at the level defined by said intermediate folding score and said glue lap fold line, said two structures being tiltable relatively to each other about a tilt axis substantially coinciding with said glue lap fold lines for freedom of the structures to tilt towards each other when the box is centrally lifted up, in which event the bottom panels assume slanted positions and the cell axes tilt outwardly, and for freedom to tilt in the opposite direction when the bottom panels are placed on a flat support, in which event the bottom portions of the two units automatically separate.
